CLUETT, PEABODY & CO., INC., OF TROY, NEW YORK, A CORPORATION OF NEW
YORK.

FOLDER FOR LOCK-END COLLAR BLANKS.

Application filed October 21, 1921. Serial No. 509,373.

To all whom it may concern:

Be it known that we, GUSTAV W. PAULSON and ROBERT H. HILL, both citizens of the United States of America, and residents of 5 Troy, in the county of Rensselaer and State of New York, have invented new and useful Improvements in Folders for Lock-End Collar Blanks, of which the following is a specification.

- 10 This invention concerns folding and pressing machines such as are commonly employed in the manufacture of collars and cuffs and relates more particularly to the folder devices employed in such machines.
- 15 In the manufacture of collars of that type having a "lock-end" difficulty is sometimes experienced in securing a proper folding of the material at the lock-end of the collar blank. This is due to the fact that at such 20 lock-end the blank is somewhat wider than at other portions, such wider portion having an edge of concave curvature merging into the substantially straight edge of the blank. In the usual type of folding machine the 25 folder blocks of each pair are mounted respectively upon folder blocks of substantially equal length, and such blocks are caused simultaneously to move inwardly in curved paths while maintaining their axial 30 alignment, thereby to wipe the margins of the blank transversely inwardly and over the edge of the die plate. When, however, the die plate is of the form necessary to the making of a lock-end collar as above referred to, the usual movement of the folder 35 blade is ineffective for folding that section of the blank comprising the concavely curved portion of the lock-end thereof, the movement of each element of the folder 40 block being substantially parallel to such edge while a movement transverse of the same is essential to proper folding. Defective work thus results from the employment of folders arranged in the usual manner 45 when utilized in making lock-end collars.

The principal object of the present invention is to provide for the mechanical folding of a lock-end collar blank, or other article having a salient or reentrant angle or 50 both, in an efficient and satisfactory manner.

To this end the invention comprises means for folding those marginal portions of the blank in the region of the salient or reentrant angle more nearly normally to the 55 edges of the blanks in such region than has

been possible with prior folding machines. The folding means preferably comprises a folder which moves at approximately the same angle to both sides of the salient or reentrant angle and which is so divided that 60 the parts move toward or from each other on opposite sides of the salient or reentrant angle along arcuate paths concave toward the bisector of said salient portion.

More specifically the invention may consist in making the folder blocks corresponding to that margin of the blank comprising the salient or reentrant edge of such unequal length that their point of junction is closely adjacent such concave edge, rather than at the 70 center of the die, the two blocks being actuated and retained in alignment by any suitable means, as for example a hinge connection. In folding lock-end collar blanks with such an arrangement the short folder block is 75 called upon to fold only the transversely extending end margin of the blank, while the motion of the longer block is such as properly to fold not only the straight edge of the blank but also the reentrant or concavely 80 curved portion of the lock-end.

In the accompanying drawings there is illustrated by way of example, a preferred arrangement of parts whereby the desired object may be attained. In these drawings:—

Fig. 1 is a plan view of a folding machine embodying the present invention, the parts being shown in the position which they occupy at the beginning of the folding operation; 90

Fig. 2 is a view similar to Fig. 1, certain parts being broken away for clearness of illustration and showing the position of the mechanism at the end of the folding operation; 95

Fig. 3 is a fragmentary rear elevation of the machine shown in Fig. 1, certain parts being omitted for clearness of illustration;

Fig. 4 is an elevation from the left-hand end of Fig. 3; and

Fig. 5 is a vertical cross section to larger scale transverse of Fig. 1.

The machine herein disclosed is of a well-known type and may, if desired, employ 105 actuating mechanism of the type disclosed for example, in the patent to Brown 1,053,477, Feb. 18, 1913. The machine comprises a table 1 carried by end supports 2 and 3. This table is provided with a longi- 110

tudinal channel or depression at its center in which is mounted the bed plate 4. Cooperating with the bed plate is a die plate 5 mounted upon a carrier 6 which in turn is supported upon an arm 7. The arm 7 is pivoted at 8 between a pair of brackets 9 secured to the machine frame, and such arm may be raised and lowered in any suitable manner, as for example by the mechanism shown in the patent to Brown above referred to.

Mounted upon the upper surface of the table are the folder blocks 10 and 11, of substantially equal length. The adjacent ends of the blocks 10 and 11 are provided with slots 12 and 13, respectively, in which are adjustably secured the slides 14 and 15. To the respective slides are pivotally secured the hinge leaves 16 and 17 which are pivotally connected together as indicated at 18. The hinge connection between the blocks 10 and 11 thus permits them to move toward and from each other in an axial direction while maintaining them in axial alignment. The remote ends of the members 10 and 11 have secured thereto the brackets 20 and 21 respectively. For retaining the members 10 and 11 in position upon the table, guide members 19 are provided. Upon the opposite side of the bed plate from the folder blocks just described is a second pair of folder blocks 22 and 23, respectively. While the blocks 10 and 11 are of substantially equal length as is usual in machines of this character, the block 22 is very much shorter than the block 23. The adjacent ends of the blocks 22 and 23 are provided with slots 24 and 25 in which are adjustably seated the slides 26 and 27 respectively. These slides serve to pivotally support the hinge leaves 28 and 29 which in turn are pivotally connected at the point 30. The blocks 22 and 23 are thus maintained in alignment while at the same time they are capable of relative endwise movement. For retaining the blocks 22 and 23 in proper position, guide members such as 31 may be employed. The remote ends of the blocks 22 and 23 have secured thereto the brackets 32 and 33 respectively.

At each end of the machine there are provided bosses such as 34 and 35 depending from the under side of the table, such bosses being provided with journal openings for the reception of vertical shafts such as 36. The upper end of each shaft is provided with an eccentric pin 37, which pins engage suitable openings in the respective brackets 20, 21, 32 and 33. The four shafts thus provided are suitably connected together for simultaneous rotation in any desired manner as, for example, as shown in the patent to Brown above referred to.

The die plate 5 is of the shape indicated in Fig. 3, having a substantially straight

edge 5^a which merges into a concavely curved edge 5^b. This die plate also has a substantially straight edge 38 intersecting the curved edge 5^b. A folder, comprising the blades 20^a, 21^a secured to the respective blocks 10 and 11, is arranged at the front of the bed plate while the folder comprising the plates 39 and 42 carried by the blocks 23 and 22 respectively, is arranged at the opposite side of the bed plate. The plate 39 is substantially co-extensive in length with the blank to be folded and has the substantially straight edge 40 merging at one end into the convexly curved portion 41. The machine as thus arranged is intended for folding collar blanks having the general shape of the die plate 5, the concavely curved end portion 5^b of which corresponds to the locking end of the collar blank.

In the operation of the machine the material having been placed upon the bed plate and the die plate 5 having been lowered to the position indicated in Fig. 1, the several shafts 36 are simultaneously rotated in the direction indicated by the arrows in Fig. 1. The result of this movement is to cause a diagonal inward movement of the folder blocks toward the center of the machine, resulting in wiping the edges of the material inwardly and transversely over the edges of the die plate. The eccentric pins 37 which actuate the blocks 22 and 23 are both disposed to the rear of the longitudinal axis of the blank and impart simultaneous movement to these blocks such that points in the edges of the plates 39 and 42 describe arcuate paths, the inner or concave sides of which are presented toward and disposed upon opposite sides of a line bisecting the salient angle of the blank being folded. By reason of the relative lengths of the blocks 22, 23 whereby their point of junction occurs closely adjacent the end of the curved portion 5^b of the die plate, it is clear that the plate 39 performs the folding operation for substantially one entire edge of the collar blank, while the blade 42 merely serves to fold the material at the end of the blank. As the movement of the blade 39 is diagonally inward at all points of its length, it serves in an efficient manner to wipe in the material across the curved portion 5^b of the die plate as well as along the straight edge 5^a of the same. Thus a proper folding of the material is secured, whereas with folder blocks of equal length such as are commonly employed, the folding of a concave edge, such as 5^b, cannot be accomplished in a satisfactory manner. While the invention has been described as particularly applicable to the folding of collar blanks having a locking end, it is contemplated that in certain of its aspects, the invention might well be employed in the folding of other articles presenting similar difficulties in folding, while

it is further contemplated that various changes and modifications in the structure for performing the desired purpose, as well as the actuating mechanism therefor, might 5 well be introduced without departing from the spirit of the present invention.

Having thus described the invention in a preferred embodiment of the same, what we 10 claim and desire to secure by Letters Patent of the United States is:

1. In a machine for folding the margins of a collar blank having a salient portion included between a longitudinal edge and end margin of the blank, a folder comprising 15 parts disposed at opposite sides of said salient portion, and means disposed wholly to one side of the longitudinal axis of the blank for simultaneously moving said parts toward each other along arcuate paths to 20 ward the respective margins of the salient portion while maintaining each part parallel to itself at all stages of its movement.

2. A machine for folding the margins of a collar blank having a salient portion included between a longitudinal edge and end margin of the blank, comprising a folder having parts simultaneously movable toward each other on opposite sides of said portion along arcuate paths concave toward 30 the bisector of said salient portion, one of said folders being constructed and arranged to fold the entire length of said longitudinal edge portion.

3. A machine for folding the margins of a collar blank provided with a salient angle adjacent to one end thereof, having a folder comprising two independently supported elements having their proximate ends located at a point adjacent to the apex of the 40 angle of the blank, and a pair of oppositely turning cranks arranged to one side of the longitudinal axis of the blank for causing said elements to move inwardly on converging lines whereby one of said elements acts 45 to fold a longitudinal margin of the blank at one side of the angle and the other element folds the end margin of the blank at the other side of the angle.

4. A folding machine for folding lock-end collar blanks comprising a folder blade substantially coextensive in length with one longitudinal edge of the blank, a second folder blade for folding the margin of the blank at the lock-end thereof, independent 55 means located adjacent to the remote ends of the respective blades, for imparting movement to the remote ends of said blades, and means whereby movement of one of said blades is transmitted to the proximate end 60 of the other.

5. A folding machine for folding lock-end collar blanks comprising aligned, relatively movable folder blocks, a folder blade secured to one of said blocks, said blade being of a length substantially coextensive 65 with one of the longitudinal edges of the blank to be folded, a folder blade secured to the other block and constructed and arranged to fold the end of the blank, and means for simultaneously moving said 70 blocks with their blades for performing the folding operation.

6. A folding machine of the class described comprising a pair of aligned folder blocks, folder blades mounted upon the respective blocks constructed and arranged respectively to fold substantially an entire longitudinal edge and an end margin of a collar blank, means connecting the proximate ends of said blocks, and means for 80 simultaneously moving the remote ends of said blocks.

7. A machine of the class described comprising a pair of aligned folder blocks, one block being substantially longer than the other, means for maintaining said blocks in alignment, and a folder blade secured to each of said blocks, that folder blade carried by the longer blocks being constructed and arranged to fold substantially one 90 entire longitudinal margin of a collar blank.

8. A folding machine for folding lock-end collar blanks comprising a short and a long folder block, means for maintaining said blocks in alignment while permitting 95 relative endwise movement thereof, short and long folder blades secured to the corresponding blocks and actuating means for simultaneously moving said blocks for respectively folding an end and edge margin 100 of a collar blank, the short blade being positioned to act upon the lock-end of the blank.

9. A machine for folding the margins of a collar, one longitudinal edge of which has a reentrant portion near one end, comprising 105 a folder divided in the region of said end, one part being movable inwardly over said end and the other part being movable inwardly over said reentrant portion, relatively movable means for supporting the respective parts of the folder, and means arranged at the same side of the longitudinal axis of the blank for simultaneously imparting operative movement to said supporting means.

Signed by me at Troy, N. Y. this 26 day of September 1921.

GUSTAV W. PAULSON.
